INVENTOR.

Barclay, C. Monroe

UNITED STATES PATENT OFFICE.

BARCLAY C. MONROE, OF NEWBURG, NEW YORK.

IMPROVEMENT IN MASON'S HODS.

Specification forming part of Letters Patent No. **145,675**, dated December 16, 1873; application filed October 8, 1873.

To all whom it may concern:

Be it known that I, BARCLAY C. MONROE, of Newberg, in the county of Orange and State of New York, have invented certain new and useful Improvements in Hods; and I do hereby declare the following to be a full, clear, and exact description of the invention, such as will enable others skilled in the art to which it pertains to make and use it, reference being had to the accompanying drawings, which form part of this specification.

The nature of my invention relates to an improvement in hods; and it consists in forming the body of the hod of a single sheet of thin steel, as will be more fully described hereafter.

The accompanying drawings represent my invention.

a represents the body of the hod, made from a single sheet of thin steel, and having the end formed by splitting one end of the sheet a sufficient distance, and then turning up the ends and riveting them together, or by forming the body by pressing it into shape at a single operation. The shape of the body may be rounding, as shown, for carrying mortar, or triangular for carrying bricks, whichever may be preferred.

Where the body is made of wood, the mortar always adheres to it, and requires to be scraped out, and then it becomes water-logged and very heavy. When made of sheet-iron, the

body soon becomes so battered and broken as to be worthless, and, having to be strengthened around the edges by iron bands, costs as much as one made of steel, while it is far inferior.

Thin steel, while it is as light as wood, will never become battered and broken, needs no strengthening bands, and can scarcely be worn out. Preferably, the body will be always stamped into shape without a single seam, and there will be no rivets to rust out, or joints to become weakened. When made of sheet-iron, rivets must always be used, and will always be a source of weakness and trouble.

After the body is completed, the socket for the handle and the usual pad will be secured thereto in any desired manner, and the hod when complete will be about one-third lighter than wood.

Having thus described my invention, I claim—

As a new article of manufacture, a hod made from a single sheet of thin steel, and stamped into the required form, substantially as shown and described.

In testimony that I claim the foregoing I have hereunto set my hand this 8th day of October, 1873.

B. C. MONROE.
